Primary Examiner — Bridget L Eland*(74) Attorney, Agent, or Firm* — Finnegan, Henderson, Farabow, Garrett & Dunner, LLP(57) **CLAIM**

The ornamental design for a phone, as shown and described.

DESCRIPTION

FIG. 1 is a front, right, top perspective view of a phone showing our new design;

FIG. 2 is a rear, left, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged rear elevation view as indicated in FIG. 4; and,

FIG. 10 is an enlarged right side elevation view as indicated in FIG. 6.

The even length broken lines immediately adjacent the shaded areas represent the bounds of the claimed design while all other broken lines are directed to environment and are for illustrative purposes only; the broken lines form no part of the claimed design. The dot-dash broken line showing of the encircled portions in FIGS. 4, 6, 9, and 10 form no part of the claimed design.

1 Claim, 10 Drawing Sheets(56)
